ENVELOPE

Eugene B. Berkowitz, Kansas City, Mo.

Application January 12, 1935, Serial No. 1,513

13 Claims. (Cl. 229—72)

This invention relates to envelopes and more particularly to those of the window type for enclosing small cards, for example automobile licenses or cards. Owing to the small size of such cards, they are likely to become lost in the mail and if they are enclosed in larger envelopes they soon become displaced relatively to the window opening so that the address thereon becomes concealed.

It is, therefore, a principal object of the invention to provide an envelope of this character with means adapted to support a card smaller than the envelope itself in a predetermined fixed position so that an address on one face of the card will at all times register with the window in the envelope.

Another important object of the invention is to provide for inspection of the card by the postal authorities.

In accomplishing these and other objects of the invention, I have provided improved details of structure, the preferred form of which is illustrated in the accompanying drawings, wherein:

Fig. 1 is a perspective view of a window envelope embodying the features of the present invention, part of which is broken away to better illustrate its construction.

Fig. 2 is a similar-perspective view of the opposite side of the envelope, the back face portion or back flap of which is broken away to better illustrate the card pocket.

Fig. 3 is a perspective view of the envelope blank.

Fig. 4 is a similar view of the blank with the pocket-forming patch applied and showing the blank partly folded.

Fig. 5 is a perspective view of the envelope illustrating the insertion of the card into the card pocket.

Fig. 6 is a perspective view of the envelope after the card is inserted in the pocket and the seal flap is ready for sealing to the back flap.

Fig. 7 is a perspective view showing the method of inspecting the front side of the card.

Fig. 8 is a similar view showing inspection of the rear side of the card.

Referring more in detail to the drawings:

1 designates an envelope blank including a front face portion 2, a back face portion or back flap 3, side flaps 4 and 5, and a seal flap 6. The front portion 2 is provided with a window opening 7 through which the address on an article contained within the envelope is visible as in ordinary window envelope construction. The

back portion 3 is of substantially the same dimensions as the front portion 2; however, the sides 8 and 9 thereof are cut back slightly from the corresponding sides of the front face portion so that they will not lie coincidentally therewith when the back flap is folded over the front face portion. The side flap 4 is sealed directly to the back flap by a strip of adhesive 10 which may be applied to the outer face of the side flap as shown in Fig. 3.

The opposite side flap 5 may be of the same shape as the flap 4 and carries a gum spot 11 on the upper inner corner thereof that seals with the overlying corner 12 of the back flap to retain the envelope in folded condition prior to sealing of the seal flap 6.

The seal flap 6 may be of conventional shape and is provided with a gum stripe 15 whereby it may be sealed over the back flap.

In order to provide a pocket within the envelope for supporting a card or similar article that is of smaller size with the address thereon in registry with the window opening 7, the back flap 3 carries a patch of transparent material 16 of slightly larger size than the dimensions of the card to provide margins 17 along the bottom edge 18 and the side edge 19 adjacent the side flap 4 which are sealed against the face of the back flap by angularly arranged adhesive stripes 20 and 21 respectively, as shown in Figs. 3 and 4.

In the illustrated instance, the adhesive stripes are located so that when the patch is secured thereby, the upper edge 22 thereof aligns with the edge 23 of the back flap to cooperate therewith in forming the respective sides of the pocket. The edge of the back flap is preferably cut away as at 24 to provide a finger-gripping portion by which the card may be readily removed from the pocket when the envelope is opened by the addressee.

With the construction thus far described, it is apparent that the end of the pocket adjacent the inspection side of the envelope is free from the back flap in order to provide an inspection opening 25 therebetween and through which the back side of the card may be inspected by the postal authorities; however, to prevent displacement of the card through the inspection opening, the upper corner of the patch is secured to the back flap by a spot of gum 26.

The spacing between the spot of gum 26 and the bottom stripe of gum 20 is less than the width of the card so that the card cannot be accidentally lost therethrough.

After the envelope blank is formed and the respective gum stripes 15, 20 and 21 are applied, to

gether with the gum spot 26, the transparent patch is attached by means of the gum stripes 20 and 21 and spot 26. The initial folds are then made by bending the side flaps 4 and 5 over the inner face of the front portion 2 and the gum strip 10 and spot 11 are applied, after which the back flap is folded over the side flaps so that the gum strip 10 sealingly engages the side flap 4 and the gum spot 11 sealingly engages the side flap 5, 10 completing the assembly of the envelope.

When the envelope is to be used by the addressee, the card designated 27 bearing the name and place of the addressee is inserted in the top opening in the pocket that is formed between the inner 15 face of the back flap and the transparent patch. In this position the address registers with the opening 7 and is visible through the transparent patch so that it can be read therethrough in the same manner as an ordinary open window envelope. 20

After insertion of the card, the gum 15 on the sealing flap is moistened and the flap sealed over the back flap, thereby closing the top opening of the pocket. With the card inserted in the pocket 25 and covered by the sealing flap, it is impossible for the card to become displaced relatively to the window opening 7.

The envelope thus prepared may be sent through the mail as ordinary third class postage since the 30 card is readily accessible for inspection by the postal authorities. For example, to inspect the contents of the envelope, it is grasped between the thumb and fingers of the hand as illustrated in Fig. 7 to cause spreading of the inspection opening so that the entire front face of the card is rendered visible due to the transparent patch.

To inspect the opposite side of the card, the finger of the other hand is inserted between the transparent patch and the back flap so that the transparent patch and card may be moved away 40 from the back flap as shown in Fig. 8 to permit view of the rear face of the card.

Attention is particularly called to the fact that the transparent patch not only permits inspection 45 of the entire face of the card, but it also forms a closure for the window opening 7 to prevent soiling of the card.

From the foregoing it is apparent that I have provided an open window envelope construction 50 equipped with a card pocket for positioning a small card therein so that an address on the card is at all times retained in registry with and is clearly visible through the open window of the envelope. It is also apparent that the card may be readily inspected by the postal authorities to 55 obtain advantage of the lower class mail rates.

What I claim and desire to secure by Letters Patent is:

1. An envelope including front and back face 60 portions and having an opening in one of said face portions, and a transparent patch fixed to the other face portion to form a pocket for supporting a card in a selected position relatively to said opening.

2. An envelope including front and back face 65 portions and having a window in one of said face portions, and a pocket formed on the inner side of the other of said face portions for supporting an article in a selected position relatively to said window.

3. In an envelope including front and back face 70 portions and having a window opening in one of said face portions, an inspection flap on one of said face portions, and a pocket constructed of 75 transparent material and located between said

face portions for supporting an article in selected position relatively to said window and having an inspection opening aligning with said inspection flap, said pocket forming a covering for said window opening to protect an article contained in the 5 pocket and through which the article is visible in said opening.

4. In an envelope including front and back face portions and having a window in one of said face portions, an inspection flap on one of said face 10 portions having one end sealed to the other of said face portions, and a pocket between said face portions for supporting an article in selected position relatively to said window and having an inspection opening aligning with said inspection 15 flap.

5. An envelope including front and back face portions and having a window in one of said face portions, and a pocket formed of a sheet of transparent material fixed to the other face portion and 20 having smaller dimensions than said face portions to support an article in selective position over said window and to cover a portion of said article registering with said window.

6. In an envelope including front and back face 25 portions and having a window in one of said face portions, an inspection flap on one of said face portions, and a pocket between said face portions for supporting an article in selected position 30 relatively to said window and having an inspection opening aligning with said inspection flap of less width than the article.

7. An envelope comprising a front face portion having a window therein, a back face portion folded over the front face portion, side flaps folded 35 over the back face portion, a seal flap foldable over the back face portion, means sealing an end of one of the side flaps to the back face portion to form an inspection opening, means sealing the other side flap with the back face portion to close 40 that side of the envelope, and a transparent patch smaller than the envelope and having edges adjacent said folded edge of the back face portion and the sealed side of the envelope affixed to the back face portion and having a corner nearest 45 said inspection opening sealed to the back face portion to provide respectively an insert opening adjacent the seal flap and an inspection opening adjacent the first-named inspection opening.

8. An envelope including front and back face 50 portions, side flaps on one of said face portions, adhesive affixing one of the side flaps to the other of the face portions, a seal flap on one of the face portions and adapted to sealingly engage the other of said face portions, and a transparent 55 rectangular patch having a pair of adjacent edges and a corner opposite said adjacent edges fixed to the inner side of one of the face portions to form a pocket having openings adjacent the seal flap and the other of said side flaps respectively. 60

9. An envelope including front and back face portions, side flaps on one of said face portions, a gum spot on one of said side flaps sealingly engaging the other face portion, adhesive sealing the other side flap to said other face portion, 65 a sealing flap on one of the face portions and adapted to sealingly engage the other of said face portions, and a transparent rectangular patch having a pair of adjacent edges and a corner opposite said adjacent edges fixed to one of the face portions to form a pocket having or adjacent the sealing flap and the side flap the gum spot respectively.

10. An envelope including front 2' portions interconnected at one of

flaps on the other edges of one of the face portions, a gum spot on one of said flaps sealingly engaging the other face portion, adhesive fixing the others of said flaps to said other face portion, and a transparent patch having a pair of adjacent sides and a corner opposite said adjacent sides fixed to one of the first-named face portions to form a pocket having inspection and insert openings adjacent the flap having the gum spot and the adjoining sealed flap.

11. An envelope including front and back face portions interconnected at one of their edges and having a window in one of said face portions, flaps on the other side edges of one of the face portions, a spot of adhesive on one of said flaps sealingly engaging the other face portion, adhesive fixing the other of said flaps to said other face portion, and a transparent patch having adjacent sides and a corner opposite said adjacent sides fixed to the inner side of one of the face portions to form a pocket in registry with said window and having inspection and insert openings adjacent said spot of adhesive and the adjoining sealed flap respectively.

12. An envelope including front and back face portions interconnected at one of their edges and having a window in one of said face portions, flaps

on the other side edges of one of said face portions, adhesive fixing an end of one of the flaps and substantially the length of the remaining flaps to said other face portion, and a transparent patch fixed to one of the face portions to form a pocket in registry with said window and having inspection and insert openings adjacent said partially sealed flap and one of the fully sealed flaps respectively.

13. An envelope comprising a face portion 10 having a window therein and provided with back and side flaps folded over said face portion and with a sealing flap foldable over the back flap, a gum spot on one of the side flaps at an end thereof nearest the sealing flap and sealingly 15 engaged with the back flap to form an inspection opening, adhesive uniting the other side flap with the back flap to close that side of the envelope, and a transparent patch having edges adjacent said folded edge of the back flap and the sealed 20 side of the envelope affixed to the back flap and having a corner nearest said gum spot sealed to the back flap to provide respectively an insert opening adjacent the sealing flap and an inspection opening adjacent the first-named inspection 25 opening.
